UNITED STATES PATENT OFFICE

2,637,552

MAGNETIC CALIPER FOR SHEET MATERIAL
HANDLING APPARATUSGeorge F. Watson, Racine, Wis., assignor to The
Christensen Machine Company, Racine, Wis., a
corporation of Wisconsin

Application April 1, 1952, Serial No. 279,871

28 Claims. (Cl. 271—57)

1

This invention, as in the application of George F. Watson, Serial No. 153,519, now abandoned, of which this application is a continuation-in-part, relates to sheet material handling apparatus such as feeders for feeding sheets of paper to printing presses and similar machines and refers particularly to a detector or caliper for stopping the apparatus upon the detection of an abnormal overlapped condition of the sheets moving to the machine being fed.

A copending application, Serial No. 153,520, filed April 3, 1950, discloses and claims the adaptation of the principle of the instant invention to caliperizing devices of general utility.

While the use of detectors or calipers for sheet material handling apparatus is not new, those heretofore employed were either pneumatic as in Patent No. 2,063,479 issued to Frank R. Belluché, or mechanical. The latter type, of which Patent No. 2,179,517 issued to M. Pelosi is an example, has cooperating feeler members, generally rollers, which have to be very accurately fitted to one another and very rigidly mounted so as to assure against any possible relative movement between their supports. This has restricted their location to the side edges of the sheet since it is impractical if not in fact actually impossible to obtain the necessary rigidity at any substantial distance in from the side edges.

Of course, it is to be understood that where the stock fed has substantial thickness, for instance cardboard, the presence of an abnormal sheet thickness is more easily detected. Deviations of a few thousandths of an inch in the spacing between the supports for the companion feelers is then not too serious; but where very thin paper, as for instance Bible stock, is being fed, such slight changes in the spacing between the supports of the feeler members are fatal to accuracy.

The pneumatic or suction type calipers of Patent No. 2,063,479 while not subject to the aforesaid limitations of the mechanical calipers cannot detect an abnormal overlap or double sheet thickness where the sheets are adhered to one another and cannot be separated by the available suction.

In recognition of these limitations of the sheet detectors and calipers heretofore available, the present invention has as its purpose to provide a caliper which will not only positively detect any abnormal sheet thickness but in addition will be reliably accurate no matter where it is located across the width of the machine. This removes the objectionable limitation upon the

2

location of the calipers which heretofore had to be at the side edges where thin stock was being fed, and in addition enables the use of any desired number of calipers side by side across the width of the machine.

A novel adaptation of magnetic force makes these advantages possible. As will appear more fully hereinafter, the present invention so utilizes the force of a permanent magnet that the companion feeler members between which the paper travels, themselves may constitute the elements of a magnet couple. In any event, the elements of the magnet couple are fixed with respect to the feeler members so that the elements of the magnet couple are moved simultaneously and directly with any movement of the feeler members. Thus, the magnetic attraction between the magnet couple directly holds the sheet engaging surfaces of the feeler members against the opposite sides of the sheet in opposition to a biasing force tending to separate the feeler members and operable, upon being released, to actuate instrumentalities for stopping the apparatus.

This novel adaptation of magnetic force enables the elements of the magnet couple to be so disposed with respect to one another that the strength of the magnetic attraction therebetween depends solely upon the spacing between the feeler members.

This invention provides, therefore, what may be termed a magnetic caliper especially adapted for use on paper sheet feeders and inspection machines, through which the slight motion obtained by relative movement between companion feeler members resulting from the detection of an abnormal overlapped condition of the sheets traveling along a defined path and passing between the companion feeler members is translated into a greatly magnified motion which takes place with a snap action and possesses considerable force.

With the above and other objects in view, which will appear as the description proceeds, this invention resides in the novel construction, combination and arrangement of parts substantially as hereinafter described and more particularly defined by the appended claims, it being understood that such changes in the precise embodiments of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a side elevational view of a sheet feeder equipped with the caliper device of this invention;

Figure 2 is a cross sectional view through the caliper device on a larger scale illustrating the same in its operative condition;

Figure 3 is a view similar to Figure 2 but showing the caliper mechanism tripped;

Figure 4 is a top plan view of the caliper mechanism with parts thereof broken away and in section;

Figures 5 and 6 are cross sectional views similar to Figures 2 and 3 but illustrating the incorporation of an inhibiting or lock-out device for the caliper;

Figure 7 is a top plan view of the structure shown in Figures 5 and 6;

Figure 8 is a front view of another adaptation of this invention, parts thereof being broken away and in section, said view illustrating one way of arranging a plurality of magnetic calipers across the width of the machine and a simplified manner of simultaneously adjusting all of the calipers to different thicknesses of stock;

Figure 9 is a front view of one form of the magnetic caliper of this invention illustrating how a horseshoe magnet may be substituted for the annular magnets used in those embodiments of the invention illustrated in Figures 1 to 8, inclusive;

Figure 10 is an end view of a magnetic caliper, which like the one shown in Figure 9, uses a horseshoe magnet;

Figure 11 is a front view of the caliper shown in Figure 10;

Figure 12 is a top view of the lower element of the magnetic caliper shown in Figure 10, said view being taken on the plane of the line 12-12 in Figure 10;

Figure 13 is an end view of a magnetic caliper or detector embodying still another modification of this invention;

Figure 14 is a diagrammatic top view of two adjacent rows of magnetic detectors of the type shown in Figure 8 arranged to encompass the full width of the passing sheets and thereby reliably inspect all portions of the sheets as they pass; and

Figure 15 is a cross sectional view through the two rows of detectors illustrating one way of mounting the movable elements thereof for independent action.

Referring now particularly to the accompanying drawings, and more specifically to the embodiment of the invention shown in Figures 1 to 4, inclusive, the numeral 5 designates generally a sheet feeder, which, as shown, may be of the continuous type wherein the supply of sheets to be fed is loaded onto the feeder in a fanned out bank. As is customary, the feeder includes separating mechanism 6 adapted to successively separate the sheets from the bank and feed them to a suitable conveying means 7 by which the sheets are carried or advanced in seriated or under-lapped relation to the press 8 or other machine being fed. The conveying means 7 includes the customary feed board 9 over which the sheets are fed in their final passage to the press and upon which the sheets are front and side registered just before entering the press, it being understood that the sheets enter the press one at a time.

Although the sheets are carried along or advanced by the conveying means in a seriated stream, the presence of two or more sheets ad-

hered to one another or any other abnormal overlapped condition of the sheets can be detected by the thickness of the stream of sheets moving to the press. Obviously, if the thickness of the stream exceeds a predetermined maximum, it is an indication that an abnormal overlapped condition exists and that the feeder should be stopped. This is the function of the caliper device indicated generally by the numeral 10.

Essentially, the caliper device 10 comprises a pair of companion feeler rollers 11 and 12 between which passes the stream of sheets S. The roller 12 which is power driven is located beneath the path of the stream of sheets S and rotates on a fixed axis. The roller 11, which is located above the path of the sheets, is carried by an arm 13 which is pivoted as at 13' upon a supporting bracket 14. The supporting bracket 14 is mounted upon a transverse shaft 15 fixed to the side frames 20 15' of the feeder, a portion of only one of which is shown. To enable the position of the caliper device to be adjusted to sheets of different widths within the range of the feeder, the bracket 14 is slidable along its supporting shaft 15 and may be locked in any position thereon. It is, of course, evident that if desired any number of caliper devices may be arranged side by side upon the shaft 15 in which case the lower rollers 12 of all of the calipers are mounted upon a common 30 drive shaft.

Swinging of the lever arm 13 about its pivot 13' raises and lowers the roller 11 as will be readily apparent, and as a correlative, up and down movement of the roller 11 from and toward its 35 companion roller 12 occasioned by variations in the thickness of the stream of sheets S passing between the rollers, imparts corresponding rocking motion to the lever arm 13.

Separation of the feeler rollers 11 and 12 is opposed by magnetic attraction therebetween. To this end a permanent magnet 16 is built into the roller 11 and the roller 12 is formed of paramagnetic material or at least is essentially of paramagnetic material. The magnet 16 is annular so that the axial ends or opposite sides 45 thereof are of opposite polarity, and to provide poles for the magnet the roller 11 is made up of two complementary facing cup-shaped halves 17 of magnetically permeable material which together house the magnet but have their edges spaced apart. While the space between the edges of the roller sections 17 could be left open, to preclude the accumulation of dirt therein and the possible bridging of the magnet poles by iron filings and the like, it is preferably filled with a suitable non-magnetic sealing compound 55 18.

The roller 11 is free to revolve about its axle 19 which is secured in the lever arm 13 so as to ride freely upon the driven roller 12, if the 60 two are in engagement, or upon the sheets passing therebetween; and by virtue of the attraction between the permanent magnet 16 and the lower roller 12 which two members constitute the elements of a magnet couple, the rollers 11 and 12 firmly clamp the sheets therebetween. Hence, the space between the peripheries of the rollers is a true measure of the thickness of the sheets passing therebetween.

The magnetic attraction which draws the rollers 11 and 12 together is opposed by a spring 20, confined between a fixed stop 21 on the bracket 14 and an adjustable stop 22 in the form of a nut threaded upon a stem 23 pivoted, as at 24, 70 to the lever arm 13 and slidably guided in the

stop 21. By means of the adjustable stop 22, the tension of the spring 20 may be so adjusted that the force of the spring is overbalanced by the magnetic attraction drawing the feeler rollers 11 and 12 together as long as the space between the peripheries of the rollers does not exceed a predetermined critical distance. When this happens the spring is freed and produces a snap action motion of considerable force. The adjustable spring stop thus provides the means by which the detector may be adjusted to stock or sheets of different thicknesses.

The spring produced motion is utilized to rock a control actuating shaft 25, and through such rocking motion thereof, actuates the control instrumentalities (not shown) by which the feeder may be stopped. Linkage 26, shown in Figure 7, connects the shaft 25 with the control instrumentalities. To enable the spring produced motion to impart such rocking movement to the shaft 25, a lever 27 is slidably splined to the shaft and carries a pin 28 at its outer end to provide an abutment against which the adjacent end of the stem 23 bears. With this arrangement, the very slight motion resulting from the movement of the roller 11 away from its companion roller 12 produced by the interpositioning of one additional sheet between the rollers is translated into a greatly magnified motion which takes place with a snap action and possesses considerable force.

This follows from the fact that as long as the elements of the magnet couple are relatively close together, as they are in this case, being separated only by the thickness of the stream of sheets, the magnetic attraction therebetween is quite strong especially if light paper sheets are being handled. In practice the magnetic pull would be on the order of twelve pounds where the distance between the feeler rollers is .004", seven pounds for twice this spacing and four pounds for three times this thickness. Hence, the reacting spring has a strong force stored therein so that whenever the spacing between the elements of the magnet couple reaches the critical distance at which the spring force overpowers magnetic attraction, a relatively powerful force is released with a snap.

In the stream feeding of sheets, the trailing portion of each sheet always overlaps the leading portion of the next adjacent sheet. Hence, the spring tension of the caliper must be adjusted to accommodate twice the thickness of a single sheet, but the addition of a third sheet thickness should trip the caliper as shown in Figure 3.

In the stream feeding of long sheets, the trailing portion of each sheet may overlap the leading portion of the sheet following the next adjacent one as shown in Figures 5 and 6. To permit such overlapping and still have the caliper set to trip in response to a third sheet thickness, an inhibitor or lock-out device is provided in that form of the invention shown in Figures 5, 6 and 7. This inhibitor or lock-cut device consists of an arm 30 keyed to a cross shaft 31 parallel to and in front of the supporting shaft 15. The shaft 31 is freely rotatable in a bearing carried by bracket 14 and has one end thereof projecting through one of the side frames of the feeder to mount driving linkage 32. This driving linkage rocks the shaft 31 to bring the arm 30 against the adjacent portion of the lever 13 just before the triple overlap to be permitted reaches the feeler rollers 11 and 12, and holds it there until this overlap passes the rollers.

To permit the slight separation of the rollers

10

15

20

25

30

35

40

45

55

65

70

necessary to pass the triple overlap, the linkage 32 is spring propelled in the direction to bring the arm 30 into operative position shown in Figure 6 and cam actuated to retract the arm as in Figure 5.

As indicated hereinbefore, the caliper rollers may be located at any point across the width of the machine, and any number of sets or pairs of caliper rollers may be employed alongside each other to provide a row of detection points extending transversely across the path of the sheets. Where such multiple points of detection are desired, it may be preferable to embody the invention in the form illustrated in Figure 8. In this case, all of the lower rollers 33 are mounted on a common driven shaft 34 journaled in bearing sleeves 35 carried by the side frames 36 of the feeder or other machine with which the device is used. Since in this case the magnet is in the lower one of the pair of rollers, each roller 33 is constructed in the manner shown in Figure 4, that is, each comprises a pair of opposed cup-shaped members 17 enclosing the annular magnet 16 but spaced apart at their peripheries by a non-magnetic spacer 18.

Non-magnetic spacers 37 are interposed between the rollers 33 and the entire assembly is clamped together to form one solid roller unit. The ends of this roller unit or assembly abut the bearing sleeves 35 which, being threaded in their respective side frames 36, may be shifted axially. This arrangement provides a convenient manner of simultaneously and quickly shifting all of the rollers 33 axially one way or the other, and to secure the same in selected adjusted positions lock nuts 33' are provided.

As will appear more fully hereinafter the axial or endwise adjustability of the lower roller unit affords a convenient and simple manner of simultaneously adjusting all of the detector or caliper units to work with different thicknesses of stock.

Since the lower rollers 33 in this case contain the magnet, the companion upper rollers 38 are of paramagnetic material. Each roller 38 is carried in a yoke 39 which is pivotally mounted as is the bracket 13 in Figure 2 so that each roller 38 is individually movable toward and from its companion.

A suitable spring arrangement diagrammatically indicated as at 40 and which may be like that illustrated in Figure 2, yieldingly urges each roller 38 upwardly and away from its companion roller 33 without affecting any of the other calipers. Thus, the passage of an abnormal overlapped sheet condition between the companion rollers of any one caliper or detector unit can be utilized to stop the mechanism in the manner hereinbefore described.

In first setting up the calipers illustrated in Figure 3 each spring 40 must be individually adjusted to the desired sheet thickness so that all of the detector units will respond to the same critical separation between rollers. Thereafter whenever it is desired to change the adjustment to accommodate different sheet thicknesses, it is only necessary to shift the lower roller assembly one way or the other to thereby bring the lower rollers 33 further into or further out of symmetry with their companion upper rollers 38. The full line position of the parts shown in Figure 3 illustrates the rollers in complete symmetry which, of course, affords the strongest magnetic attraction between the rollers since in this position the reluctance of the magnetic circuit is least, whereas in the dotted line position

of the lower roller assembly the magnetic attraction between the rollers is greatly diminished because of the assymmetrical disposition of the rollers of each pair and the consequent increase in reluctance in the magnetic circuit.

Obviously, of course, the magnet could be mounted in the upper roll as it is in the previously described embodiments of the invention. In this case the lower roll assembly would consist of a series of collars of paramagnetic material separated by non-magnetic spacers. Either arrangement lends itself admirably to the adaptation of this invention to the inspection of sheet material or separate sheets where it is essential that the entire area thereof be calipered. Such an adaptation of the invention is diagrammatically illustrated in Figure 14 where sheets S' move successively along a defined path between two rows of detector units R and R'.

Each of the two rows of detector units consists of a continuous lower roller assembly 41 and a series of independent upper rollers 42. The lower roller assembly 41 may contain the magnets as in the structure shown in Figure 8, and as there indicated is mounted for axial adjustment in the manner described in connection with Figure 8.

The upper rollers 42 thus are independently mounted for movement toward and from their companion bottom rollers, and it is important to observe that the relative spacing of these upper rollers with respect to their widths is such that the upper rollers of one row ride upon the surface of the sheets lying between the upper rollers of the other row. In other words, the upper rollers of the two rows are staggered to assure that the entire area of the sheets will be calipered.

Though the manner in which the upper rollers 42 are mounted may be varied to suit different conditions and may follow the arrangement shown in Figure 2 for instance, a convenient and compact arrangement for the mounting of these upper rollers is illustrated in Figure 15. As here shown each roller 42 is carried by a lever-like bracket 43 pivoted as at 44 upon a crosshead 45. All of the crossheads 45 are slidably mounted upon two parallel transverse supporting rods 46 so that the upper rollers 42 can be axially adjusted with respect to each other as needed to effect the desired staggered relationship and assure the entire area of the sheets being calipered.

Each lever-like bracket 43 is individually yieldingly urged by a spring 47 to lift its roller 42 and, as hereinbefore described, such spring-propelled movement of the movable roller takes place whenever the thickness of the sheets passing between the caliperating rollers exceeds the predetermined critical value.

Upon spring-produced movement of any one of the lever-like brackets 43 one or the other of two actuating shafts 48 is rocked. To this end the brackets 43 are each individually connected with one of the shafts 48 through a link 49 and a lever 50, the latter keyed to the shaft 48. Lost motion is provided in the connections between the links and levers as shown to allow the actuated bracket 43 to rock its shaft without hindrance from the rest of the mechanism.

The rocking of either one of the shafts 48 may be utilized in any suitable manner either to stop the passage of sheets upon detection of an abnormal overlapped condition or to control mechanism (not shown) by which an imperfect sheet will be discarded, but since the specific way in

which such response is utilized to effectuate the desired result forms no part of this invention, it is sufficient to diagrammatically illustrate the same as has been done in Figure 15 wherein a switch 51 connected with each of the two shafts 48 closes a circuit controlling the mechanism to be actuated, whenever either shaft is rocked.

In all of the embodiments of the invention described thus far the magnet has been annular and actually embedded in one of the two cooperating rollers. It is, of course, also possible to utilize the more conventional horseshoe magnet without deviating from the spirit or scope of this invention and those modifications of the invention shown in Figures 9 to 13, inclusive, use this more conventional form of magnet.

Thus, in Figure 9 the upper roller 52 is formed of any suitable non-magnetic material and is mounted in a yoke 53 to which a horseshoe magnet 54 is securely fastened.

The ends or poles of this horseshoe magnet lie in a plane spaced slightly above the horizontal plane tangent to the underside of the roller 52 so as to be spaced slightly from the adjacent surface of the lower roller 55 which coats with the roller 52 and is formed of paramagnetic material. The magnet couple in this case, of course, constitutes the lower roller 55 and the horseshoe magnet 54, but since the horseshoe magnet 54 is fixed with respect to the axis of the upper roller 52 it follows that the strength of the magnetic attraction between the elements of the magnet couple depends solely upon the spacing between the rollers.

In the embodiment of the invention illustrated in Figures 10, 11 and 12, the horseshoe magnet 56 is disposed horizontally with its legs embracing the sides of the lower roller 57 which, in this case, is of non-magnetic material carried by a drive shaft 58 journalled in a bearing bracket 59. The bearing bracket 59 also has the horseshoe magnet secured thereto so that the magnet will be fixed with respect to the axis of the roller 57; and though any suitable manner of mounting the bracket 59 may be employed it is convenient

to secure the same to a transverse supporting rod 60 by means of a set screw so that the position of the bracket 59 may be adjusted across the width of the machine.

In this embodiment of the invention the upper roller 61 is of paramagnetic material and is carried by a bracket 62 to move up and down as in Figure 2.

The embodiment of the invention illustrated in Figure 13 differs from those previously discussed in that neither one of the rollers need be of paramagnetic material. Accordingly a horseshoe magnet 63 embraces the lower roller 64 and is held in fixed relation to the axis thereof by having the bearing bracket 65 in which the roller is journalled fixed to the bight of the horseshoe magnet. The poles of the magnet are secured to the underside of a horizontal supporting plate 66 of non-magnetic material which in turn is mounted upon a transverse supporting shaft 67.

The upper roller 68, which as indicated may be of non-magnetic material, is carried by a supporting bracket 69 pivotally mounted upon a cross shaft 70. A spring 71 yieldingly urges the roller 68 away from its companion, but the spring is resisted by the magnetic attraction between the horseshoe magnet 63 and an armature 72 of paramagnetic material. The armature 72 is fixed with respect to the axis of the upper roller 68, being mounted upon the axle of the roller as

shown, and an adjusting screw 73 reacting against a spring 74 enables the armature to be brought into absolute parallelism with the supporting plate 63 and consequently the pole faces of the horseshoe magnet.

The operation of this embodiment of the invention is, of course, the same as that hereinbefore described since, as in all previous instances, the separation of the rollers beyond a predetermined critical distance enables the spring to overpower the magnetic attraction and thus impart a snap action movement to the movable element of the detector unit.

From the foregoing description taken in connection with the accompanying drawings, it will be readily apparent to those skilled in the art that the present invention provides a caliper device for sheet feeders, sheet inspecting machines, and sheet material handling machines generally which is simple in construction and positive in its operation, and which is not limited in its application to the side edges of the sheets but may be located at any position across the width of the machine with assurance of absolute accuracy and without the need for heavy supporting structures. This follows from the fact that any deviation of the stationary one (described and shown as the bottom one) of the pair of feeler rollers caused by flexure or vibration of its supporting shaft or by any other cause which might be encountered in machines of this type, in nowise affects the functioning or positiveness of the caliper since in this case the other roller of the pair (the upper one) merely rises and falls with the stationary roller without tripping the mechanism as long as the spacing between the rollers does not exceed the critical distance for which the mechanism has been set by the adjustment of its spring tension.

What I claim as my invention is:

1. In a sheet material handling machine including conveyor means by which the sheet material is carried along a defined path, means for effecting a predetermined response of control instrumentalities for said machine upon passage along said defined path of an abnormal condition in the thickness of the sheet material, comprising: a pair of cooperating rollers positioned to engage the opposite faces of sheet material moving along said defined path so that such sheet material must pass between the rollers; means mounting one of said rollers for movement toward and from the other; a body of paramagnetic material fixed with respect to the axis of one of the rollers and positioned to be directly adjacent to one face of the sheet material being carried along by the conveyor means, a magnet firmly fixed with respect to the axis of said other roller and positioned to lie directly adjacent to the other face of the sheet material passing between the cooperating rollers, the poles of said magnet being in juxtaposition to said body of paramagnetic material so that the strength of the magnetic attraction between the magnet and said body of paramagnetic material depends solely upon the spacing between the rollers; biasing means acting upon the movable roller and yieldingly urging the same away from the other, said biasing means being overpowered by the magnetic attraction between the magnet and said body of paramagnetic material as long as the spacing between the rollers does not exceed a predetermined critical distance but moving the rollers farther apart the instant the spacing therebetween exceeds said predetermined critical

distance; and means actuated by the separation of the rollers by the biasing means and operable in consequence to such actuation to effect the desired response of the control instrumentalities.

5. 2. In a sheet material handling machine: a pair of cooperating feeler members between which the sheet material passes with its opposite faces in direct contact therewith so that the thickness of the sheet material determines the spacing between the feeler members, one of said feeler members being movable toward and from the other; a movable control member forming part of control instrumentalities for the machine; a connection between the movable control member and the movable feeler member through which an appreciable movement of the feeler member away from its companion actuates the control member; a body of paramagnetic material fixed with respect to one of the feeler members and positioned to be directly adjacent to one face of the sheet material passing between said cooperating feeler members; a magnet firmly fixed with respect to the other feeler member and positioned at the other face of the sheet material passing between the feeler members, with the poles of the magnet in juxtaposition to said body of paramagnetic material so that the strength of the magnetic attraction between the magnet and said body of paramagnetic material depends solely upon the spacing between the cooperating feeler members; and biasing means yieldingly urging the movable feeler member away from its companion and thereby tending at all times to actuate the control member, said biasing means being overpowered by the magnetic attraction between the magnet and said body of paramagnetic material as long as the feeler members are spaced apart less than a predetermined distance so that separation of the feeler members in excess of said distance as by the interpositioning of an abnormal condition in the thickness of the sheet material passing between the feeler members overpowers the force of magnetic attraction.
10. 3. In a sheet caliper mechanism for a sheet material handling machine: a pair of cooperating feeler members between which the sheet material passes, one of said members being movable toward and from the other; a movable control member forming part of control instrumentalities for the machine; an operable connection between the movable control member and the movable feeler member through which a substantial movement of the feeler member away from its companion actuates the control member; biasing means yieldingly urging the movable feeler member away from its companion and thereby tending at all times to so actuate the control member; a permanent magnet mounted in one of said feeler members and having its poles facing the other feeler member; and said other feeler member being essentially of paramagnetic material so that the feeler members are magnetically drawn together in opposition to said biasing means and the biasing means is restrained as long as the feeler members are spaced apart less than a predetermined distance, separation of the feeler members in excess of said distance, as by the interpositioning of an abnormal condition in the thickness of the sheet material passing between the feeler members, enabling the biasing means to overpower the force of magnetic attraction drawing the feeler members together.
15. 4. In a sheet feeder having separator mech-

anism for successively separating sheets from a source thereof and conveyor means for advancing such separated sheets in seriated relation along a defined path to a machine to be fed, means for stopping the feeder upon the detection of an abnormal overlapped condition of the stream of sheets moving along said conveyor means, comprising: companion feeler rollers positioned to engage the opposite faces of the stream of sheets being advanced by the conveyor means so that the stream of sheets passes between the rollers; means mounting one of said rollers for rotation about a fixed axis; a pivoted support for the other roller by which said other roller is movable toward and from the first roller; a movable control member operable to effect stopping of the feeder; a connection between the movable control member and said pivoted support through which movement of the pivoted support in the direction to separate the rollers actuates the control member; biasing means urging said pivoted support in said direction and thus tending at all times to separate the rollers; a permanent magnet within one of said rollers; and the other roller being of paramagnetic material so that the two feeler rollers constitute a magnet couple and the magnetic attraction therebetween draws the rollers together in opposition to said biasing means, said biasing means being overpowered by the magnetic attraction between the elements of the magnet couple as long as the spacing between the rollers which is determined by the thickness of the stream of sheets passing therebetween is less than a predetermined critical distance.

5. The apparatus set forth in claim 4 further characterized by the provision of means operating in timed relation with the feeder restraining the biasing means notwithstanding its release by separation of the rollers the critical distance so that a regularly recurring overlapped condition of the sheets does not trip the mechanism.

6. In a sheet feeder for feeding sheets from a source of supply to a printing press or other machine to be fed and including a conveyor for carrying the sheets along a defined path to the machine being fed, means for detecting the passage along said defined path of an abnormal condition in the thickness of the sheets and for actuating a control member, comprising: companion feeler members each having a sheet engaging surface; means mounting and positioning said feeler members with their sheet engaging surfaces facing each other and in position to engage the opposite faces of sheets moving along said defined path so that the sheets pass therebetween, the mounting means for one of said feeler members providing for movement thereof toward and from its companion; a magnet embodied in one of the feeler members, and the other feeler member having a paramagnetic portion defining its sheet engaging surface so that said feeler members are drawn together by the magnetic attraction therebetween; biasing means acting upon the movable feeler member and yieldingly urging the same away from its companion, said biasing means being overpowered by the magnetic attraction between the feeler members as long as the spacing between their sheet engaging surfaces does not exceed a predetermined critical distance but separating the feeler members whenever the spacing between said surfaces exceeds the critical distance; and a movable control member actuated by the biasing means upon release of the biasing means.

7. In a sheet material handling machine hav-

ing control instrumentalities to be actuated upon the detection of an abnormal sheet thickness: conveyor means for advancing the sheet material along a defined path; a pair of cooperating feeler members; means mounting and positioning the feeler members with their sheet engaging surfaces facing each other and in position to engage the opposite faces of the sheet material advancing along said defined path; the mounting means for one of said feeler members providing movement of said member toward and from the other; a movable actuating member for the control instrumentalities; an operable connection between the movable actuating member and the movable feeler member through which movement of said feeler member beyond a predetermined distance away from its companion operates said actuating member to actuate the control instrumentalities; biasing means yieldingly urging the movable feeler member away from its companion and thereby tending at all times to so operate the actuating member; a permanent magnet constituting part of one of the feeler members, and said feeler member having spaced magnetically permeable portions providing poles for the magnet and also the sheet engaging surface of said feeler member; and the other feeler member being essentially of paramagnetic material and bridging said poles of the magnet so that the feeler members are drawn toward each other by magnetic attraction, whereby said movable feeler member is restrained by said magnetic attraction against being moved by the biasing means as long as the feeler members are spaced apart less than said predetermined distance.

8. In a sheet material handling machine for advancing sheet material along a defined path and having control instrumentalities to be activated upon the detection of an abnormal condition in the thickness of the sheet material being advanced along said path, a magnetic caliper for detecting such an abnormal condition and thereupon activating the control instrumentalities, said magnetic caliper comprising: a pair of companion rollers having their axes parallel; means mounting one of the rollers with its axis disposed crosswise of the path of the sheet material and its periphery in position to engage one face of the sheet material advancing along said path; means mounting the other roller with its periphery in position to engage the opposite face of said sheet material and for movement toward and from its companion; one of said rollers comprising a permanent magnet between axially spaced portions of magnetically permeable material which form poles for the magnet; the other roller being essentially of paramagnetic material so as to magnetically bridge said poles whereby the two rollers are drawn together by magnetic attraction; a spring acting upon the mounting for the movable roller and tending at all times to separate the rollers, said spring being overpowered by the magnetic attraction between the rollers as long as the space between them does not exceed a predetermined critical distance; and an actuating member for the control instrumentalities drivingly connected with the mounting for the movable roller and operable by spring produced movement thereof.

9. In a sheet feeder having conveyor means for feeding sheets from a source of supply to a discharge point and instrumentalities to be actuated upon the detection of an abnormal condition in the thickness of the sheets being fed, means for detecting such an abnormal condition, comprising: companion feeler rollers; means mounting

the feeler rollers in position to engage the opposite faces of the sheets being fed and for relative movement toward and from one another; one of said rollers comprising a pair of complementary disc-like sections of magnetically permeable material spaced apart a slight distance at their rims; a permanent magnet confined between said sections and so disposed that said sections provide poles for the magnet; the other roller being of paramagnetic material so as to magnetically bridge said poles and be attracted towards its companion; biasing means acting in opposition to said magnetic attraction and operable to separate the feeler rollers when the spacing therebetween exceeds the critical distance at which the magnetic attraction overpowers the biasing means; a control element for operating the instrumentalities governed by the detector; and a driving connection which operates in accordance with separation of the feeler rollers by the biasing means to impart movement to the control element.

10. A machine for inspecting sheet material and detecting an abnormal condition in the thickness thereof, comprising: conveyor means for advancing the sheet material along a defined path; a plurality of pairs of companion feeler rollers; means mounting said pairs of companion feeler rollers side by side in a row extending transversely across the path of the sheet material with one roller of each pair positioned to have its periphery engage one face of the advancing sheet material and the other roller positioned to have its periphery engage the opposite face thereof, the mounting means for one roller of each pair providing for movement thereof independently of all other rollers toward and from its companion; separate means biasing the movable roller of each pair away from its companion; a permanent magnet for one roller of each pair arranged with the poles thereof fixed with respect to the axis of its roller and in juxtaposition to the companion roller of the pair, the companion roller being essentially of paramagnetic material so that the rollers are magnetically attracted to one another in opposition to the force of the biasing means tending to separate them, the strength of the magnetic attraction between the rollers depending upon the distance between the rollers so that upon separation of the rollers beyond a critical distance at which the force of the biasing means overpowers the magnetic attraction, as by the interpositioning of an abnormal condition in the thickness of the sheet material passing between the rollers, the biasing means moves the movable roller away from its companion; a movable actuating member; a motion transmitting connection between the mounting means for the movable roller of each pair of rollers and said actuating member through which motion of any one of the movable rollers produced by the biasing means operates the actuating member; and control instrumentalities connected with the actuating member to be activated thereby.

11. The machine set forth in claim 10 further characterized by the fact that the pairs of companion feeler rollers are axially spaced apart; and further characterized by the provision of a second actuating member and a second row of similar companion feeler rollers disposed in staggered relationship with the companion feeler rollers of the first row with the fields of coverage of the rollers in one row overlapping those of the other row; and further characterized by the fact

that said control instrumentalities are responsive to operation of the actuating member of either row of feeler rollers.

12. In a sheet material handling machine of the character described: conveyor means for advancing sheet material along a defined path; a plurality of pairs of companion feeler rollers; means mounting said pairs of companion feeler rollers side by side in a row extending transversely across the path of the sheet material with one roller of each pair positioned to have its periphery engage one face of the advancing sheet material and the other roller in position to have its periphery engage the opposite face thereof; the mounting means for one roller of each pair providing for movement thereof toward and from its companion; separate means biasing the movable roller of each pair away from its companion; a permanent magnet for one roller of each pair arranged with the poles thereof fixed with respect to the axis of its roller and in juxtaposition to the companion roller, said companion roller being essentially of paramagnetic material so that the rollers of each pair are magnetically attracted toward one another in opposition to the force of the biasing means tending to separate them, the strength of the magnetic attraction between the rollers of each pair depending upon the distance between them and their relative axial dispositions so that upon separation of the rollers of any pair beyond a critical distance at which the biasing means overpowers the magnetic attraction, as by the interpositioning of an abnormal condition in the thickness of the sheet material passing between them, the biasing means acting on the movable roller of that pair moves it away from its companion; control instrumentalities operated by the motion of any one of the movable rollers produced by the biasing means; and means for simultaneously shifting all of the rollers at one side of the defined path of travel of the sheet material as a unit axially with respect to the rollers at the other side thereof to thereby simultaneously change the effectiveness with which the magnetic attraction between the rollers opposes the springs.

13. In a magnetic caliper of the character described: a pair of companion feeler rollers; means mounting one of said rollers for movement toward and from the other; means for passing sheet material to be calipered between said rollers; biasing means acting upon the movable mounted roller tending to move it away from its companion; a permanent magnet fixed with respect to the axis of one of the rollers with its poles facing the other roller and in juxtaposition thereto, said other roller being essentially of paramagnetic material so that the rollers are magnetically drawn together in opposition to the biasing means tending to separate them, the strength of the magnetic attraction depending upon the thickness of the sheet material between the rollers and the relative axial disposition of the rollers so that upon the interpositioning of an abnormal condition in the thickness of sheet material passing between the rollers the biasing means overpowers the magnetic attraction and separates the rollers; and means for shifting one of the rollers axially with respect to the other roller to thereby change the strength of the magnetic attraction drawing the rollers together.

14. In a magnetic caliper of the character described: a unitary roller assembly comprising a series of magnet rollers and non-magnetic spacers arranged alternately upon a common shaft;

a movable companion roller for each of said magnet rollers, said movable companion rollers being essentially of paramagnetic material; a separate mounting for each of said movable rollers by which it may be moved toward and from its magnet roller; separate biasing means acting upon the mounting means of each of said movable rollers and tending to separate it from its companion magnet roller; and means for shifting the roller assembly axially with respect to the movable companion rollers to thereby simultaneously alter the reluctance of the magnetic circuit of each pair of rollers whereby the critical distance of separation between the rollers at which the biasing means overpower magnetic attraction may be simultaneously adjusted for all pairs of rollers.

15. In a sheet handling machine including conveyor means by which the sheet material is carried along a defined path, means for effecting a predetermined response of control instrumentalities for said machine upon passage along said defined path of an abnormal condition in the thickness of the sheet material, comprising: a pair of cooperating rollers positioned with their axes transverse to the path of the sheet material and their peripheries engageable with the opposite faces of sheet material moving along said path so that such sheet material must pass between the rollers; means mounting one of said rollers for movement toward and from the other; a body of paramagnetic material fixed with respect to the axis of one of the rollers and positioned to be directly adjacent to one face of the sheet material being carried along by the conveyor means; a horseshoe magnet embracing the other roller and fixed with respect to the axis thereof with its poles positioned to lie directly adjacent to the other face of the sheet material passing between the cooperating rollers and in juxtaposition to said body of paramagnetic material so that said rollers are drawn together by the magnetic attraction between the magnet and the body of paramagnetic material with a force depending solely upon the spacing between the rollers; biasing means acting upon the movable roller and yieldingly urging the same away from the other, said biasing means being overpowered by the magnetic attraction between the horseshoe magnet and said body of paramagnetic material as long as the spacing between the rollers does not exceed a predetermined critical distance but moving the rollers apart the instant the spacing therebetween exceeds said predetermined critical distance; and means actuated by the separation of the rollers produced by the biasing means and operable in consequence to such actuation to effect the desired response of the control instrumentalities.

16. The structure set forth in claim 15 wherein said body of paramagnetic material is in the form of a bar separate from its associated roller but mounted upon the axle thereof with the outer face of the bar lying in a plane radially inward of the periphery of the roller; wherein the horseshoe magnet embraces the other roller with its poles opposite the end portions of said bar of paramagnetic material; and means for adjusting said bar of paramagnetic material about the axle of its roller to enable the maintenance of uniform spacing between the poles of the horseshoe magnet and the end portions of said bar.

17. In a magnetic caliper: a magnet couple consisting of a magnet element and an armature element mutually attracted toward one an-

other, one of said elements being movable toward and from the other; a spring applying a force upon the movable element in a direction tending to separate the elements of the magnet couple; 5 said elements of the magnet couple having feeler surfaces drawn toward each other by the magnetic attraction between said elements and between which work to be calipered may be passed, said elements engaging opposite faces of said work and being held by magnetic attraction against spring propelled separation beyond the thickness of said work as long as the spacing between their said feeler surfaces remains less than a critical distance at which the magnetic 10 attraction between the elements overpowers the spring so that the interpositioning of work having a thickness at least as great as said critical distance for which the caliper is set will cause said spring to overcome said magnetic attraction permitting said movable element to be moved out of engagement with the work by the spring.

15. A caliper of the character described, comprising: a magnet couple consisting of a magnet element and an armature element mutually attracted toward each other; one of said elements being movable toward and from the other; an indicator responsive to movement of the movable element away from the other element; feeler surfaces on said elements between which work to be calipered is passed, said feeler surfaces being engaged with opposite faces of said work by the magnetic attraction of said elements; and a spring acting upon the movable element in opposition to the magnetic attraction between said elements to move the same and actuate the indicator whenever the elements of the magnet couple are separated beyond a predetermined distance by work having a thickness greater than said pre-determined distance.

19. In a caliper of the character described: a permanent magnet having a work engaging surface; a member of magnetic material, means mounting the permanent magnet for movement in a defined path toward and from a work engaging reference surface on said member, said surfaces engaging opposite faces of work to be calipered; a spring applying a unidirectional force upon the permanent magnet, said spring being overpowered by the magnet as long as the permanent magnet is less than a predetermined critical distance from the reference surface, but overpowering the magnet and moving the same out of engagement with the work whenever the space between the work engaging surface of the magnet and the work engaging reference surface exceeds said predetermined critical distance; indicator means responsive to spring propelled movement of the permanent magnet, whereby said indicator means is activated whenever the thickness of a layer of non-magnetic material between the work engaging surface of the permanent magnet and the work engaging reference surface separates the same more than the critical distance for which the caliper is set; and means for adjusting the tension of the spring to set the caliper.

20. In a magnetic caliper of the character described: a magnet couple comprising a permanent magnet having a work engaging surface and a block of magnetic material having a complementary work engaging surface; means mounting said elements of the magnet couple in opposed relation with their work engaging surfaces facing each other so that the magnetic attraction between the magnet and the block tends

to draw their work engaging surfaces together, one of said elements being movable toward and from the other; biasing means acting upon said movable element and at all times urging the same away from the other element to thus separate their work engaging surfaces; and instrumentalities actuated by movement of the movable element produced by the biasing means so that whenever work to be calipered is passed between said elements with opposite faces of the work engaged by the work engaging surfaces of said elements of the magnet couple which reduces their mutual magnetic attraction by increasing the spacing therebetween to the point where the biasing means overpowers the magnetic attraction, said instrumentalities will be actuated in response to movement of said movable element by said biasing means.

21. In a magnetic caliper for non-magnetic material, a magnet couple comprising a magnetized element and an armature element magnetically attracted toward one another, said elements having feeler surfaces engaging directly opposed faces of the material being calipered, said engagement being effected by the magnetic attraction of said elements, and one of said elements being movable toward and away from the other, support means for said elements, biasing means operably connected with and continuously applying a yieldable force upon the movable element, said force being applied in a direction tending to further separate said elements and to disengage said movable element from said material, the biasing force and the force of magnetic attraction being so proportioned that the movable element is held in engagement with the surface of said material as long as the thickness of the material interposed between said feeler surfaces in less than a critical distance at which

the biasing force overpowers the force of magnetic attraction between the elements and said movable element is moved out of engagement with the material when material having a thickness at least as great as said critical distance is interposed between said feeler surfaces.

5 22. Apparatus as defined in claim 21 wherein the magnetized element is movable and the armature element is fixed.

10 23. Apparatus as defined in claim 21 wherein the armature element is movable and the magnetized element is fixed.

15 24. Apparatus as defined in claim 21 wherein the magnetized element comprises a permanent magnet.

25. Apparatus as defined in claim 21 wherein the biasing means comprises a spring.

20 26. Apparatus as defined in claim 21 wherein at least one of the elements of the magnet couple is a roller.

27. Apparatus as defined in claim 21 wherein the magnetized element and the armature element are rollers.

22 28. Apparatus as defined in claim 21 wherein 25 the movable element of the magnet couple is a roller.

GEORGE F. WATSON.
